(57) **CLAIM**

The ornamental design for a door lining for vehicle as shown and described.

DESCRIPTION

The patent or application file contains at least one drawing executed in color. Copies of this patent or patent application publication with color drawing(s) will be provided by the Office upon request and payment of the necessary fee.

1. Door lining for vehicle

1.1 : Front

1.2 : Back

1.3 : Left

1.4 : Right

1.5 : Top

1.6 : Bottom

1.7 : Perspective

FIG. 1.1 to FIG. 1.7 are drawings showing an embodiment of a door lining for vehicle. The broken lines and the perspective area with dark blue in the drawings show portions of the door lining for vehicle which form no part of the claimed design.
